CUT-OUT

Neil A. Dey, Toronto, Ontario, Canada, assignor
to Dominion Cutout Co. Limited, Toronto, Ontario, Canada

Application October 17, 1936, Serial No. 106,122
In Canada November 20, 1935

17 Claims. (Cl. 200—114)

This invention relates to cut-outs of the "drop-out" type, that is cut-outs in which the fuse cartridge is held in circuit-closing position by means of movable parts which are held in latching position through the instrumentality of the fuse link, whereby upon the fusing of said link, said movable parts are released and thus allow the fuse cartridge to move out of circuit-closing position.

10 The object of the present invention is to devise improved interengaging contact and latch means controlled by the fuse link, for holding the fuse cartridge in its circuit-closing position.

I attain my object by providing on or in a support a U-shaped contact, the legs of which are resilient and formed with inclined spreader portions between which is received a wedge-shaped yoke member slidable longitudinally of the fuse cartridge. Spring means are provided tending 20 to move the yoke member out of its latching position between the legs of the U-shaped contact, said yoke member, however, being normally held in its latching position by means of the fuse link.

The construction is hereinafter more specifically described and is illustrated in the accompanying drawing in which

Fig. 1 is a vertical section of the cut-out,

Fig. 2 a transverse section on the line 2—2 in Fig. 1; and

30 Fig. 3 a detail front view illustrating the latching means between the fuse cartridge and the support;

Fig. 4 a sectional detail on the line 4—4 in Fig. 3; and

35 Fig. 5, a vertical sectional detail through the upper cartridge terminal, the parts being in released position.

In the drawing like numerals of reference indicate corresponding parts in the different 40 figures.

1 indicates a box-type housing of insulating material and having an open bottom and front, said front, however, being provided with a door 2, also of insulating material and hingedly 45 mounted adjacent the lower end of the housing.

In the housing are mounted contact or terminal members A and B which are adapted to be engaged by terminal members C and D mounted on the door.

50 The terminals C and D support the fuse cartridge 3, each being provided with a hole into which the cartridge extends and preferably the cartridge extends some distance below the lower terminal C as shown.

Mounted on the upper terminal D is a movable

wedge-shaped contact member 4, which is provided with a guide portion 24 which extends into the terminal D. A coil spring 5 is interposed between the terminal D and the contact member 4 and tends to move said contact member 4 upwardly. An annular shoulder 26 at the lower end of the guide portion 24 limits the upward movement of the contact member 4.

The wedge-shaped member 4, however is normally held in its lower position by means of 10 the fuse link 6, which is provided with a head 7 which engages the top of said contact member. The other end of the fuse link passes around the end of the cartridge and is secured about a post 8, being clamped in position by a nut 9 threaded 15 on said post.

It will be understood however, that I do not desire to restrict myself to the particular form of fuse link shown, or to the method shown of securing the lower end of the fuse link, as other 20 methods may readily be devised, one convenient form of fuse link and method of fastening being shown in the Tate Canadian Patent No. 327,268.

The lower terminal A in the housing which operates with the terminal C comprises a base 25 10 which may be secured in the housing in any suitable manner, although I show it provided with a U-shaped securing clip 11, the legs of which are resilient and are provided with out-turned ends which engage in notches 23 in the 30 inner wall of the housing. The base 10 is provided with a recess 12 for receiving the end of a conductor, one or more set screws 13 being provided for securing the conductor in place. On the base is mounted a brush contact 14, which 35 comprises a series of spring leaves, which engage and complete the electrical contact with the lower terminal C on the door. The brush contact 14 of course tends through its engagement with the terminal C, to move the door 2 to open 40 position.

The upper terminal B in the housing co-operates with the terminal D to complete the circuit and also to hold the door 2 closed. This terminal B, like the terminal A, comprises a base 15, a 45 U-shaped securing clip 16, the legs of which are resilient and provided with outturned ends for engagement in notches 23. This base is also provided with a recess 17 to receive the end of the conductor and with set screws 18 to secure 50 the conductor in place.

Also mounted on the base is a U-shaped latch member or keeper 19, which engages the wedge-shaped contact member 4 on the terminal D to hold the door closed with the fuse cartridge 55

in circuit-closing position. The opposed legs of this latch member 19 are bent to form shoulders 20 which engage the contact member 4 to prevent accidental disengagement of the latter.

5 The ends of the legs of the latch member 19 are out-wardly flared to facilitate engagement with the contact member 4.

Adjacent the shoulders 20 and at the side nearest the base 15 the legs of the U-shaped member 19 are inclined as shown at 21 to correspond with the shape of the contact member 4, the inclination being such that there is a tendency, if the contact member is not held down by the fuse link, for said contact member to be 15 moved upwardly by the latch member.

As there is danger of cracking or chipping the porcelain housing or door when closing the latter, I prefer to employ a U-shaped spring member 22, which is secured to the base 15, and prevents direct contact or engagement between the door and housing.

The operation of the device is as follows. As stated above the wedge-shaped contact member is held in its lower position by the fuse link, and 25 as long as the contact member is so held the latch member will engage the contact member and thus hold the door closed.

Upon the blowing of the fuse, the wedge-shaped contact member 4 under the action of 30 the spring 5 will be raised allowing it to be disengaged from the shoulders 20 and thus allowing the door to open and carry the fuse cartridge to circuit breaking position. This opening of the door is facilitated by the pressure exerted on the lower terminal C by the brush contact 14. The open door is, of course, an indication as to where a fuse link requires replacement.

To ensure a perfect contact between the upper 40 end of the fuse link and the wedge-shaped contact member, a set screw 25 is threaded through the wall of the latter and jams the link against the side of the hole. This set screw 25 is further utilized to effect a gastight closure of the opening through the wedge-shaped member, the diameter of the screw being greater than that of the hole for the fuse link. From this it follows that when the set screw is screwed home, the said hole for the fuse link is completely closed.

50 It will be evident that the important feature of my invention is the co-operating constructions of the upper terminals B and D, and while the arrangement has been described and shown in connection with a cut-out of the enclosed type 55 it will be apparent that the arrangement may be employed in and will operate equally as well in an open-type cutout.

What I claim as my invention is:—

1. In a cut-out, the combination of a container 60 of insulating material, a cover hinged to the container, spaced terminals on said cover for supporting a fuse cartridge, spaced terminals in the container for engaging the terminals on the cover, one of said terminals in the container 65 comprising a U-shaped contact clip having a shoulder thereon adjacent the outer end of each leg, the co-operating terminal on the cover comprising a wedge-shaped contact member slidable longitudinally on the cartridge and which said U-shaped contact clip is adapted to engage; and a fuse link having one end connected with said wedge-shaped member to hold it in engagement with the contact clip.

70 2. In a cut-out, the combination of a container of insulating material, a cover hinged to the container, spaced terminals on said cover for supporting a fuse cartridge, spaced terminals in the container for engaging the terminals on the cover, one of said terminals in the container com-

the container, spaced terminals on said cover for supporting a fuse cartridge, spaced terminals in the container for engaging the terminals on the cover, one of said terminals in the container comprising a U-shaped contact clip having a shoulder thereon adjacent the outer end of each leg, the co-operating terminal on the cover comprising a wedge-shaped contact member slidable longitudinally on the cartridge and which said U-shaped contact clip is adapted to engage; the 10 surfaces of said contact clip with which the wedge-shaped member engages being inclined to correspond with said wedge-shaped member; and a fuse link having one end connected with said wedge-shaped member to hold it in engagement 15 with the contact clip.

3. In a cut-out, the combination of a container of insulating material, a cover hinged to the container, spaced terminals on said cover for supporting a fuse cartridge, spaced terminals in the 20 container for engaging the terminals on the cover, one of said terminals in the container comprising a U-shaped contact clip having a shoulder thereon adjacent the outer end of each leg, the co-operating terminal on the cover comprising 25 a contact member slidable longitudinally on the cartridge and which said U-shaped contact clip is adapted to engage; spring means tending to move said member out of engagement with said clip; and a fuse link having one end connected with said wedge-shaped member to hold it in engagement with the contact clip.

4. In a cut-out, the combination of a container of insulating material, a cover hinged to the container, spaced terminals on said cover for supporting a fuse cartridge, spaced terminals in the container for engaging the terminals on the cover, one of said terminals in the container comprising a U-shaped contact clip having a shoulder thereon adjacent the outer end of each leg, the 30 co-operating terminal on the cover comprising a wedge-shaped contact member slidable longitudinally on the cartridge and which said U-shaped contact clip is adapted to engage; spring means tending to move said member out of engagement with said clip; and a fuse link having one end connected with said wedge-shaped member to hold it in engagement with the contact clip.

5. In a cut-out, the combination of a container of insulating material, a cover hinged to the container, spaced terminals on said cover for supporting a fuse cartridge, spaced terminals in the container for engaging the terminals on the cover, one of said terminals in the container comprising a U-shaped contact clip having a shoulder thereon adjacent the outer end of each leg, the co-operating terminal on the cover comprising a wedge-shaped contact member slidable longitudinally on the cartridge and which said U-shaped contact clip is adapted to engage; the 40 surfaces of said contact clip with which the wedge-shaped member engages being inclined to correspond with said wedge-shaped member; spring means tending to move said member out of engagement with said clip; and a fuse link having one end connected with said wedge-shaped member to hold it in engagement with the contact clip.

6. In a cut-out, the combination of a container of insulating material, a cover hinged to the container, spaced terminals on said cover for supporting a fuse cartridge, spaced terminals in the container for engaging the terminals on the cover, one of said terminals in the container com-

prising a U-shaped contact clip having a shoulder thereon adjacent the outer end of each leg, the co-operating terminal on the cover comprising a wedge-shaped contact member slidable longitudinally on the cartridge and which said U-shaped contact clip is adapted to engage; and a fuse link having one end connected with said wedge-shaped member to hold it in engagement with the contact clip, the other terminal in the container normally tending to move the cover to open position.

7. In a cut-out, the combination of a support, a fuse cartridge hingedly mounted on said support; spaced terminals on the fuse cartridges; spaced terminals on the support for engaging the terminals on the cartridge, one of said terminals on the support comprising a U-shaped contact clip having a shoulder adjacent the outer end of each leg, the co-operating terminal on the cartridge comprising a wedge-shaped contact member slidable longitudinally of the cartridge and which said U-shaped contact clip is adapted to engage, and a fuse link having one end connected with said wedge shaped member to hold it in engagement with the contact clip.

8. In a cut-out, the combination of a support; a fuse cartridge hingedly mounted on said support; spaced terminals on the support for engaging the terminals on the cartridge, one of said terminals on the support comprising a U-shaped contact clip having a shoulder adjacent the outer end of each leg, the co-operating terminal on the cartridge comprising a wedge-shaped contact member slidable longitudinally of the cartridge and which said U-shaped contact clip is adapted to engage, the surfaces of said contact clip with which the wedge-shaped member engages being inclined to correspond with said wedge-shaped member; and a fuse link having one end connected with said wedge-shaped member to hold it in engagement with the contact clip.

9. In a cut-out, the combination of a support; a fuse cartridge hingedly mounted on said support; spaced terminals on the fuse cartridge; spaced terminals on the support for engaging the terminals on the cartridge, one of said terminals on the support comprising a U-shaped contact clip having a shoulder adjacent the outer end of each leg, the co-operating terminal in the cartridge comprising a contact member slidable longitudinally of the cartridge and which said U-shaped contact clip is adapted to engage, spring means tending to move said member out of engagement with said clip, and a fuse link having one end connected with said contact member to hold it in engagement with the contact clip.

10. In a cut-out, the combination of a support; a fuse cartridge hingedly mounted on said support; spaced terminals on the fuse cartridge; spaced terminals on the support for engaging the terminals on the cartridge, one of said terminals on the support comprising a U-shaped contact clip having a shoulder adjacent the outer end of each leg, the co-operating terminal on the cartridge comprising a wedge-shaped contact member slidable longitudinally of the cartridge and which said U-shaped contact clip is adapted to engage; spring means tending to move said member out of engagement with said clip; and a fuse link having one end connected with said wedge shaped member to hold it in engagement with the contact clip.

75 11. In a cut-out, the combination of a support;

a fuse cartridge hingedly mounted on said support; spaced terminals on the fuse cartridge; spaced terminals on the support for engaging the terminals on the cartridge, one of said terminals on the support comprising a U-shaped contact clip having a shoulder adjacent the outer end of each leg, the co-operating terminal on the cartridge comprising a wedge-shaped contact member slidable longitudinally of the cartridge and which said U-shaped contact clip is adapted to engage; the surfaces of said contact clip with which the wedge-shaped member engages being inclined to correspond with said wedge-shaped member; spring means tending to move said member out of engagement with said clip, and a fuse link having one end connected with said wedge shaped member to hold it in engagement with the contact clip.

12. In a cut-out, the combination of a support; a fuse cartridge hingedly mounted on said support; spaced terminals on the fuse cartridge; spaced terminals on the support for engaging the terminals on the cartridge, one of said terminals on the support comprising a U-shaped contact clip having a shoulder adjacent the outer end of each leg, the co-operating terminal on the cartridge comprising a wedge-shaped contact member slidable longitudinally of the cartridge and which said U-shaped contact clip is adapted to engage, and a fuse link having one end connected with said wedge-shaped member to hold it in engagement with the contact clip; the other terminal on the support normally tending to move the cartridge to open position.

13. In a cut-out, the combination of a container of insulating material, a cover hinged to the container, spaced terminals on said cover for supporting a fuse cartridge, spaced terminals in the container for engaging the terminals on the cover, one of said terminals in the container comprising a U-shaped contact clip having a shoulder thereon adjacent the outer end of each leg, the co-operating terminal on the cover comprising a wedge-shaped contact member slidable longitudinally on the cartridge and which said U-shaped contact clip is adapted to engage; said wedge-shaped member having an opening therethrough in alinement with the bore of the cartridge into which one end of the fuse link extends, and a set screw extending through said wedge-shaped member for securing the end of the fuse link in position, the diameter of said set screw being greater than the width of the opening through the wedge-shaped member.

14. In a cut-out, the combination of a container of insulating material, a cover hinged to the container, spaced terminals on said cover for supporting a fuse cartridge, spaced terminals in the container for engaging the terminals on the cover, one of said terminals in the container comprising a U-shaped contact clip having a shoulder thereon adjacent the outer end of each leg, the co-operating terminal on the cover comprising a contact member slidable longitudinally on the cartridge and which said U-shaped contact clip is adapted to engage; spring means tending to move said member out of engagement with said clip; and a fuse link having one end connected with said wedge-shaped member to hold it in engagement with the contact clip; said contact member having an opening therethrough in alinement with the bore of the cartridge into which one end of the fuse link extends, and a set screw extending through said contact member for securing the end of the fuse link in position, the

diameter of said set screw being greater than the width of the opening through the contact member.

- 5 15. In a cut-out, the combination of a container of insulating material, a cover hinged to the container, spaced terminals on said cover for supporting a fuse cartridge, spaced terminals in the container for engaging the terminals on the cover, one of said terminals in the container having a pair of spaced arms, the co-operating terminal on the cover having a wedge-shaped contact member slidable longitudinally of the cartridge into and out of cover-holding position and with which said arms are adapted to engage; a 10 fuse link having one end connected with said wedge-shaped member to hold it in cover-holding position; and means normally engaging said wedge-shaped member to hold the door closed when said wedge-shaped member is in engagement with said arms.
- 15 16. In a cut-out, the combination of a container of insulating material, a cover hinged to the container, spaced terminals on said cover for supporting a fuse cartridge, spaced terminals in the container for engaging the terminals on the cover, one of said terminals in the container having a pair of spaced arms, the co-operating terminal on the cover having a wedge-shaped contact member slidable longitudinally of the cartridge into and out of circuit-closing position and with which said arms are adapted to engage; a 20 fuse link having one end connected with said wedge-shaped member to hold it in circuit-closing position; and means normally engaging said wedge-shaped member to hold the cartridge in circuit-closing position when said wedge-shaped member is in engagement with said arms.
- 25

cartridge into and out of cover-holding position and with which said arms are adapted to engage; a fuse link having one end connected with said wedge-shaped member to hold it in cover-holding position; spring means tending to move said wedge-shaped member out of cover-holding position; and means normally engaging said wedge-shaped member to hold the door closed when said wedge-shaped member is in engagement with said arms.

10 17. In a cut-out, the combination of a support having a pair of spaced terminals thereon; a fuse cartridge, spaced terminals on said cartridge for engaging the terminals of the support, said cartridge being hingedly connected with the support, one of said terminals on the support having a pair of spaced arms, the co-operating terminal on the cartridge having a wedge-shaped contact member slidable longitudinally of the cartridge into and out of circuit-closing position and with which said arms are adapted to engage; a fuse link having one end connected with said wedge-shaped member to hold it in circuit-closing position; and means normally engaging said wedge-shaped member to hold the cartridge in circuit-closing position when said wedge-shaped member is in engagement with said arms.
